(57) **CLAIM**

The ornamental design for a mobile terminal case, as shown and described.

DESCRIPTION

FIG. 1 is a perspective view of a mobile terminal case;
FIG. 2 is a front view of the mobile terminal case of FIG. 1;
FIG. 3 is a rear view of the mobile terminal case of FIG. 1;
FIG. 4 is a left-side view of the mobile terminal case of FIG. 1;
FIG. 5 is a right-side view of the mobile terminal case of FIG. 1;
FIG. 6 is a top plan view of the mobile terminal case of FIG. 1;
FIG. 7 is a bottom plan view of the mobile terminal case of FIG. 1; and,
FIG. 8 is a perspective view of the mobile terminal case illustrating an example of how the mobile terminal case may be docked to a mobile terminal that is shown in broken lines. The broken line drawing of a mobile terminal is for illustrative purpose only and forms no part of the claimed design.
